DESIGN FOR A PERFUME APPLICATOR

Jorge Biro, Buenos Aires, Argentina

Application December 4, 1946, Serial No. 135,265

Term of patent 14 years

(Cl. D86—10)

To all whom it may concern:

Be it known that I, Jorge Biro, a citizen of Hungary, residing at Buenos Aires, Argentina, have invented a new, original, and ornamental Design for Perfume Applicators, of which the following is a specification, reference being made to the accompanying drawing.

In the drawing Fig. 1 is a side view, Fig. 2 a top view, and Fig. 3 a bottom view of a perfume applicator, showing my new design.

I claim:

The ornamental design for a perfume applicator, as shown.

JORGE BIRO.
